(57) **CLAIM**

The ornamental design for a dehumidifying, deodorizing and wrinkle-reducing machine for clothing, as shown and described.

DESCRIPTION

1. Dehumidifying, deodorizing and wrinkle-reducing machine for clothing

1.1 : Perspective

1.2 : Front

1.3 : Back

1.4 : Left

1.5 : Right

1.6 : Top

1.7 : Bottom

1.8 : Perspective shown in use

The broken lines depict portions of a dehumidifying, deodorizing and wrinkle-reducing machine for clothing that form no part of the claimed design. The display shown in broken lines in 1.8 forms no part of the claimed design.

1 Claim, 8 Drawing Sheets
